UNITED STATES PATENT OFFICE

CARL LAWRENCE MATTISON, OF ROCKFORD, ILLINOIS, ASSIGNOR TO MATTISON MACHINE WORKS, OF ROCKFORD, ILLINOIS, A CORPORATION OF ILLINOIS

ABRADING MACHINE

Application filed April 8, 1926. Serial No. 198,509.

This invention relates to abrading or polishing machines and refers more particularly to that type in which an endless abrading or polishing belt is applied to the work piece by means of a reciprocating presser shoe which bears upon one run of the traveling belt.

The general object of the invention is to produce a machine in which the reciprocating path of the shoe is not only adjustable in length but longitudinally shiftable on the machine for the purpose of working most efficiently on irregularly shaped stock, for example, such as the tops of grand pianos.

In my prior Patents Nos. 1,478,044 and 1,478,575 there are disclosed machines of this type wherein an endless abrading belt traverses the work in slightly spaced relation thereto which belt is adapted to be pressed onto the work by a reciprocating shoe on the inner side of the endless belt. In said patents there are shown and described means for oscillating the shoe along the lower run of the belt and also means for varying both the speed and the length of the stroke of the presser shoe. The mechanism for controlling the motion of the shoe in the machines of said patents has been shown as fixedly mounted in the center of the machine bed. By the construction of the prior machines in order to shift the path of the reciprocating shoe, it has been necessary to unclamp the shoe from the steel tape which actuates it and to reposition the shoe on the band in a different place.

The aim of the present invention is to provide means to effect shifting of the path of reciprocation relative to the work without stopping the shoe for the purpose.

A further object is to provide means for shifting both the tape and the shoe as a unit with a motion in addition to the reciprocation.

A particular object is to provide the shoe actuating mechanism on a carriage movable along the length of the machine whereby to permit shifting the center of reciprocation in accordance with the shape of the work and further to provide a simple hand controlled power connection for shifting the carriage.

In the accompanying drawings I show by way of example a machine which represents the preferred embodiment of my invention, and it should be understood that the following detailed description of this particular embodiment is given only for the sake of imparting an understanding of the invention as applied to the machines of the patents. I do not intend hereby to limit the invention to the precise construction disclosed in the drawings but aim to cover all modifications, equivalents and alternative constructions falling within the scope of the appended claims.

In the drawings, Figure 1 is a front elevational view of the improved machine.

Fig. 2 is a plan view.

Fig. 3 is a detailed cross sectional view of the machine on the line 3—3 of Fig. 2.

Referring to the drawings the supporting frame of the machine comprises the end pedestals 1 and 2, the lower connecting member 3 and the top 4 which serves as the bed of the machine. On the pedestals are guides 5 on which brackets 6 and 7 are vertically adjustable, said brackets having the horizontal rails 8 and 9 for rollers 10 and 11, which support a work holding platform 12. The platform is thus vertically adjustable and horizontally shiftable on the machine frame. Inasmuch as any suitable means well known in this art may be used for vertically adjusting the brackets 6 and 7, I have deemed it unnecessary to illustrate such adjusting mechanism.

At the left end of the bed 4 there is a transversely extending drive shaft 13 driven through gearing 14 by a motor 15. The shaft 13 has a pulley 16 at its front end which drives an abrading belt 17, which passes over a similar pulley 18 at the right end of the machine. The pulley 18 is mounted on a transverse shaft 19 which is laterally adjustable by means of a suitable mechanism generally designated 20.

At its rear end the driving shaft has a beveled gear 21 meshing with a second beveled gear 22 on a shaft 23 positioned longitudinally of the machine. The shaft 23 has a longitudinal keyway 24 therein for splin-

ing thereon a beveled gear 25 carried in a bracket 26. The beveled gear 25 meshes with a gear 27 rigid on a shaft 28 and parallel with the drive shaft 13.

5 The bed of the machine (Fig. 3) has longitudinal ways 29 and 30 upon which a head or carriage 31 is adjustably mounted. The carriage 31 contains the shoe controlling mechanism and receives power through the 10 shaft 28 (Fig. 2) which bears in the rear right hand portion of the carriage 31. The splined shaft 23 and the carriage thus cooperate to permit adjustments without affecting the distribution of power.

15 In order to make clear the general arrangement of the major parts of the machine a brief description of the essential parts thereof is here given.

20 There is provided a reciprocating steel tape parallel with the runs of the sanding belt 17 and preferably mounted between them. A rail or track parallels the band to provide support for the presser shoe which is adapted to act upon the belt and to 25 press it onto the work. A plurality of parallel rods are associated with the track for the shoe and serve to movably support the track and shoe to permit raising the shoe from the belt after the shoe has been unclamped or freed from the reciprocating 30 steel tape. The reciprocation of the tape is controlled by suitable speed power connections and suitable stroke adjusting mechanism as will hereinafter appear. The detailed structure of the parts will be found 35 in the above mentioned patents.

40 The numeral 32 represents a shoe which runs on a rail or track 33. The rail is supported for motion vertically by a parallelogram link mounting. On each end of the machine bed 4 there are mounted a pair of brackets 34 each pair carrying an upper horizontal bar 35 (Fig. 3) and a lower horizontal bar 36, the bars being parallel in a 45 vertical plane. A horizontal link 37 pivoted on bar 35 pivotally supports a forward upper bar 38. A forward lower bar 39 is supported from the lower rear bar 36 by a horizontal link 40 and from bar 38 by a 50 vertical link 41. This vertical link extends below the four parallel bars and has an L projection 42 thereon which carries the rail or track 33. The parallel linkage above described thus supports the shoe for vertical 55 motion. A weight 42^a is used to counterbalance the shoe, said weight being adjustably mounted on a link pivotally secured to the two upper bars 35 and 38.

60 On the ends of the machine bed there are transverse shafts 43, each of which has at the forward end a drum or wheel 44 and at the rear end a pinion 45. A steel tape 46 is stretched from one drum to the other being wound on each in order to reciprocate 65 as the shafts carrying the drums oscillate

70 together. At the rear of the machine upstanding brackets 47 support gear segments 48 which mesh with the pinions 45. The two segments 48 are interconnected by a link 49 for synchronous oscillation. A driving rod 50 serves to oscillate one of the gear segments thus causing each segment to act on its pinion 45 to reciprocate the steel tape 46. On the shoe there is provided a handle 51 which when properly controlled operates 75 clamping mechanism associated with the shoe by which the shoe is made to clamp the tape. The details of the mechanism may be found in the cited patents.

80 On the movable carriage 31 there is a driven shaft 52 which carries a disk wheel 53. In the wheel 53 there is a diametrical way 54. A slidable head 55 moves in the way 54 to vary the eccentricity thereof. A portion 56 of the head is pivotally related to the sliding portion mounted in the way and is formed so as to receive and clamp the end of driving rod 50. Suitable mechanism, 85 not shown, is provided to adjust the eccentricity of the slidable head while the shaft 52 rotates, the mechanism including a worm screw 57 engaging the head 55 and a control member 58 for the operator to regulate the eccentricity, thereby to vary the stroke of the shoe. In Figs. 2 and 3 there is shown 90 suitable mechanism for disengaging and for varying the speed ratio of the power connection between the driving shaft 28 and the driven shaft 52 of the movable head or carriage 31. A description of the parts is herein omitted since they form no part of the 95 present invention.

100 In order to permit shifting of the center of the stroke of the shoe without uncoupling the shoe from the belt a displacement of the band is made. This is best effected by moving the carriage 31. It is clear that the carriage can be moved without effecting its driving shaft 52 because the driving shaft 28 is driven by a splined connection with shaft 23. The driving rod 50 merely moves the gear segments to a new operative position without materially effecting the length of the stroke. Because of the large ratio between the gear segments 48 and the pinions 45 a slight movement of the carriage is considerably multiplied in shifting the band.

110 In order to shift the carriage, a feed screw 60 is provided longitudinally of the bed, there being a nut member 61 on the carriage 31 projecting through a slot 62 of the bed 4. A power feed for the screw is preferred and is associated with a conveniently located 115 manual control. In the machine of the drawings the feed screw 60 is located in a plane below the main driving shaft 13. A counter shaft 63 is therefore provided below shaft 13 parallel therewith. Speed reducing gears 64 and 65 are provided between 120

the two shafts. A bevel clutch two-way transmission mechanism of well known character is provided between the shaft 63 and the feed screw shaft 60, said mechanism being generally designated 66 and containing a shiftable collar 67. A shifting lever 68 for said collar extends downwardly and forwardly of the machine and is provided with a handle 69 for the operator to control the power connection.

In operating upon an irregularly shaped work piece represented by the grand piano top W, the device is set so that the work initially operates with its stroke centered over the center of the work on the wide edge. The parts can readily be adjusted properly first, by positioning the wheel 53 with its diametrical way vertically disposed. The shoe 32 is then clamped over the center of the work, that is, the center of the wide edge of the piano top W. The stroke of the shoe is adjusted by moving the head 55 along the way 54 so that when the way 54 is horizontally disposed the shoe is at the desired limit. As the work moves progressively through the machine to a point where the rear curved portion of the work piece W is located it is evident from Fig. 1 that the work on the right end of the original long path of reciprocation will be wasted. Therefore, it is desirable that the stroke be both shortened and shifted to traverse only the narrower rear portion of the work piece. The shortening of the stroke can be readily accomplished through the control 58 which causes the eccentricity of the head 55 to vary, thereby shortening the stroke of rod 50. At the same time the control member 68 is moved to allow the power from the driving shaft to move the carriage. This imparts to the gear segments a rotation in addition to their oscillation and thereby moves the belt and shoe to shift the path of the reciprocating shoe. It is clear that any skilled workmen experienced with the machine can readily cause the shoe to change its location and its path of reciprocation with the advance of the work without necessitating a stopping of the machine and without unclamping the shoe from the band.

I claim as my invention:

1. An abrading machine comprising, in combination, an abrading element, a reciprocating shoe adapted to apply said abrading element to a piece of work, a tape to move the shoe, synchronously oscillatory drums upon which the tape is wound and unwound to move the shoe, a shaft for one of said drums, a pinion on said shaft, a toothed element meshing with said pinion, said element being movable in a manner to oscillate the drums, a normally stationary head, means carried by said head to effect a motion of said toothed element for oscillating the drums and reciprocating the tape, and means

to move the head to shift the paths of oscillation and reciprocation.

2. An abrading machine comprising, in combination, an abrading element, a reciprocating shoe adapted to apply said abrading element to a piece of work, a steel tape to move the shoe, synchronously oscillatory drums upon which the tape is supported to move the shoe, a driving member, a crank operable thereby to oscillate the drums, means to support said crank adjustably relatively to said drums, and means to move said supporting means bodily whereby to shift the reciprocating tape and shoe.

3. An abrading machine comprising, in combination, an abrading element, a reciprocating shoe adapted to apply said abrading element to a piece of work, a tape to move the shoe, interconnected rotary drums upon which the tape is wound to move the shoe, a crank arm arranged on oscillation to move said drums, means to oscillate said arm, and other means to displace said arm to displace the path of reciprocation of the tape and shoe.

4. An abrading machine comprising, in combination, an abrading element, a reciprocating shoe adapted to apply said abrading element to a piece of work, a steel tape to move the shoe, interconnected rotary drums upon which the tape is wound and to move the shoe, means to oscillate the drums to reciprocate said shoe, and means to impart an angular displacement to said drums independently of their oscillatory movement whereby to shift the path of reciprocation of the shoe.

5. An abrading machine comprising, in combination, an abrading element, a reciprocating shoe adapted to apply said abrading element to a piece of work, a steel tape to move the shoe, power driven means to effect a reciprocation of the tape, and means to displace the tape in its direction of reciprocation independently of the reciprocating movement thereof and while said reciprocating movement continues.

6. An abrading machine comprising, in combination, an abrading element, a reciprocating shoe adapted to apply said abrading element to a piece of work, power-driven means to reciprocate the shoe over a determinable path, and means controllable during the operation of the machine to displace said reciprocating means to shift the center of the path of reciprocation with respect to the work.

7. In a machine of the class described, a movable carriage containing mechanism to control the speed and stroke of a reciprocating element which is mounted independently thereof, a connecting rod having one end mounted on the carriage to effect reciprocation of the element, and means to

move the carriage to shift said rod for shifting the path of reciprocation.

8. In a machine of the character described having a reciprocatory shoe carried by a tape moved by an oscillating drum system, the combination of power-driven means arranged during the operation of the machine to provide a continuous oscillation of said drum system, and means operable to modify the effect of the power-driven means whereby to superimpose upon the oscillating motion of the drum system an angular displacement whereby to shift the path of the reciprocating shoe.

15. An abrading machine comprising a base frame, a pair of pulleys mounted on said frame, a sanding belt on said pulleys, a pressure shoe for applying said belt to the work, and means to operate said shoe, said means comprising an oscillatory member supported on said base frame and connected to said shoe, a carriage on said frame slidable parallel to the movement of said shoe, a crank mounted on said carriage and having a pitman connection with said oscillatory member, means to actuate said crank and means to adjust said carriage on said frame whereby to adjust the path of application of said shoe.

30. 10. In a machine of the class described the combination of a reciprocatory shoe, power-driven means to reciprocate said shoe and means to superimpose a positive displacement to said shoe independent of said reciprocatory movement while said reciprocatory movement continues.

40. 11. In a machine of the class described the combination of a reciprocatory shoe, means to reciprocate said shoe rectilinearly, power-driven means to adjust the length of the path of reciprocation of the shoe, and means to displace said path independently of said reciprocatory movement while said reciprocatory movement continues.

45. 12. In a machine of the character described, the combination of a frame, a reciprocatory shoe supported thereon, and means to reciprocate said shoe including a carriage adjustable on said frame to shift the path of reciprocation of said shoe during such reciprocatory movement, a power driven crank rotatably mounted thereon, mechanism connecting said crank and said shoe whereby the oscillation of said crank causes said shoe to reciprocate and means to adjust the length of said crank.

50. 13. In a machine of the character described, the combination of a reciprocatory shoe, power-driven means to reciprocate said shoe, means to determine the length of stroke of said reciprocation, and means independent of and separate from said stroke determining means for altering the effect of said power-driven means so as to cause 55 said shoe to reciprocate over a different por-

tion of the work while said shoe continues to reciprocate.

14. In a machine for abrading the tops of grand pianos, the combination of an abrading element, a shoe adapted to apply said abrading element to the top, power-driven mechanism operable to produce relative reciprocatory movement between said shoe and the top, mechanism to determine the length of stroke of said reciprocatory movement so as to cause it to equal the width of the top at the particular part then being abraded, and mechanism independent and separate from said stroke determining mechanism for moving the center of the path of reciprocation, when the stroke is less than full width of the machine, to coincide with the center of the width of the top at the particular part then being abraded, while said reciprocatory movement continues.

15. In an abrading machine, the combination of a work support, an abrading element, a reciprocatory shoe to apply said abrading element to the work, a support for said shoe, power-driven mechanism to reciprocate said shoe, means connecting said mechanism to the shoe, a support for said mechanism and means operable to move one of said supports whereby to shift the path of reciprocation relatively to the work.

16. In a machine of the character described having a frame, a reciprocatory shoe movably mounted with respect to the frame, a tape connected to said shoe, an oscillating drum system supporting said tape and operable to reciprocate said shoe, power-driven means operable to oscillate said drum system, means connecting said power-driven means to said drum system, and means operable to superimpose upon the normal oscillating motion of the drum system an angular displacement whereby to shift the path of the reciprocating shoe, said means comprising a support for said power-driven means movably mounted on said frame.

In testimony whereof, I have hereunto affixed my signature.

CARL LAWRENCE MATTISON.
